FIG. 1 is a bottom front left side perspective view of an electronic device showing our new design;

FIG. 2 is a bottom front right side perspective view thereof;

FIG. 3 is a front view thereof;

FIG. 4 is a rear view thereof;

FIG. 5 is a left side view thereof;

FIG. 6 is a top view thereof;

FIG. 7 is a bottom view thereof;

FIG. 8 is a bottom front left side perspective view of a second embodiment of our new design;

FIG. 9 is a front view thereof;

FIG. 10 is a rear view thereof;

FIG. 11 is a left side view thereof;

FIG. 12 is a bottom front right side perspective view of a third embodiment of our new design;

FIG. 13 is a left side perspective view thereof;

FIG. 14 is a front view thereof;

FIG. 15 is a rear view thereof;

FIG. 16 is a left side view thereof;

FIG. 17 is a left side perspective view of a fourth embodiment of our new design;

FIG. 18 is a front view thereof;

FIG. 19 is a rear view thereof;

FIG. 20 is a left side view thereof;

FIG. 21 is a left side perspective view of a fifth embodiment of our new design;

FIG. 22 is a front view thereof;

FIG. 23 is a rear view thereof;

FIG. 24 is a left side view thereof;

FIG. 25 is a left side perspective view of a sixth embodiment of our new design;

FIG. 26 is a front view thereof;

FIG. 27 is a rear view thereof; and,

FIG. 28 is a left view thereof.

The electronic device in all of the Figures is identical except for the color of a portion of the electronic device. FIGS. 1-7 show contrasting appearance, but no particular color is claimed.
